GARMENT HANGER

Arthur M. Framke, Chicago, Ill.

Application March 18, 1947; Serial No. 735,355

5 Claims. (Cl. 223—88)

1

This invention relates to garment hangers. The main objects of this invention are, to provide a garment hanger having an improved arrangement of means whereby many pieces of various kinds of clothing may be simultaneously suspended in orderly and readily-accessible arrangement; to provide an improved hanger of this kind which is capable of being supported in garment-suspending position from any one of several conventional means used for such purpose; to provide an improved construction of individual garment-suspending elements each adapted for separable attachment to the articles of clothing and to the garment-supporting hanger itself; and to provide an improved garment hanger of this kind which is extremely simple in construction, therefore very economical to manufacture, and exceedingly convenient to use.

A preferred embodiment of this invention is shown in the accompanying drawings in which:

Fig. 1 shows the improved garment-suspending bar mounted on a wire coat hanger but equipped with a strap element and formed with apertures whereby it might be supported either on a rod or on a hook rail;

Fig. 2 is a fragmentary detail in perspective showing the manner in which the garment-supporting bar is yieldingly retained in place on the coat hanger;

Fig. 3 is an enlarged end elevation of the arrangement shown in Fig. 1 as viewed from the plane of the line 3—3;

Fig. 4 is a reduced view showing a pair of trousers suspended from the arrangement shown in Fig. 1;

Fig. 5 is a reduced fragmentary detail showing in full and in dotted outlines how a pair of garment-suspending bars may be secured either to the bottom or the top edge respectively of a hook rail, the view including an indication of how two pairs of trousers might be suspended from such an adjacent pair of bars;

Fig. 6 is an enlarged partly sectional end view of the arrangement shown in Fig. 5 as viewed from the plane of the line 6—6;

Fig. 7 shows in full and in dotted outlines a garment-suspending tab secured to the inside of the waist of the garment;

Fig. 8 is an enlarged side elevation of the upper end of the tab showing the oppositely disposed arrangement of a pair of the socket parts of a conventional snap fastener; the figure being in juxtaposition to Fig. 3 shows the upper socket part of the snap fastener in axial alinement with

2

the ball part of the snap fastener shown in Fig. 3; and

Fig. 9 is a side elevation of a garment-suspending tab showing at the upper end a pair of oppositely-disposed socket parts of a snap fastener and at the lower end a flap hinged thereto and by means of which it would be convenient to permanently attach the tab to the inside of a garment.

10 The preferred form of garment hanger constructed in accordance with this invention comprises a bar 10 whereon is mounted a row of parts 11 of a conventional snap fastener wherefrom may be suspended tabs 12 to which are secured the other parts 13 of the aforesaid type snap fasteners. The tabs 12 are formed or equipped with means for attaching them to garments which are to be suspended from the bar 10. Hooks 14, apertures 15, and an inverted 15 stirrup member 16 are formed on, in, or attached to the bar 10 to permit it to be supported on any one of several different types of support.

The bar 10 preferably, although not necessarily, is formed of plastic material. As shown in the 20 drawings, the upper longitudinal perimeter is formed to provide a flange 17 (see Fig. 2) to fit over the horizontal part 18 of a conventional wire coat hanger 19. Hooks 14 are formed at the ends and at an intermediate point of the flange 17 and so shaped that they will yieldingly receive the transverse part 18 of the coat hanger 19 and secure the bar 10 against accidental displacement thereon.

The fastener parts 11 and 13, as herein shown, 25 are of the conventional ball and socket type. A plurality of the ball parts 11 of these snap fasteners are arranged in a row longitudinally of the bar 10 so that the tabs 12 may be removably suspended at various points thereon by the engagement of the socket parts 13 with the ball parts 11, in the obvious manner.

The tabs 12 preferably are pieces of fabric of appropriate construction each mounting a pair 30 of the socket parts 13 of the snap fasteners at the upper end and a safety pin 20 or flap 21 at the lower end for removably or permanently attaching the tab to a garment. Intermediate its ends each tab 12 is formed with a buttonhole 22 whereby the tab, when it is to be used for suspending trousers, may be attached temporarily to the buttons conventionally arranged on the inside waistline of trousers.

As will be clearly noted from the drawings, the pair of socket parts 13 of the snap fasteners secured to a tab 12 are oppositely disposed. This

permits a tab to be attached to the complementary part 11 on the bar 10 regardless of how the tab may be attached to the garment.

As will be obvious from Fig. 7, the tab may remain attached to the inside of the garment and allowed to drop down within the garment, as shown in dotted outline, when the garment is to be worn. This avoids the necessity of finding tabs or attaching them to a garment when the garment is to be suspended from the hanger.

The apertures 15, of which there are three shown in the drawings (see Fig. 1), permit the bar 10 to be attached by means of screws or nails to the upper or lower edge of a closet hook rail 23, as shown in Figs. 5 and 6.

The inverted stirrup member 16 preferably is in the form of a strap of fabric or leather, or even plastic material. On each end is secured the socket part 13 of a snap fastener which permits the strap to be attached to a pair of adjacent ball parts 11 so that by means of the strap the bar parts 11 may be suspended from a rod or pole 24.

On occasion the bar 10, mounted on a coat hanger as shown, could be suspended from a post or over a chair or a bed end. If the bar were removed from the hanger 19 it might be supported from the back of a chair by means of the hooks 14.

Other variations and modifications in the details of structure and arrangement of the parts may be resorted to within the spirit and coverage of the appended claims.

I claim:

1. A garment hanger of the class described comprising, a bar, a plurality of one part of a two-piece snap fastener arranged on said bar in a row longitudinally thereof, a plurality of garment-suspension elements each having secured thereto the other part of the aforesaid two-piece snap fastener, means on each of said elements for attaching said element to a garment, said bar having a plurality of hooks formed along one edge thereof adapted to support said bar on the cross-bar of a conventional coat hanger, said bar also having apertures formed therein whereby said bar may be anchored to a hook rail or the like, and an inverted stirrup means attached to said bar whereby it may be suspended from a rod.

2. A garment hanger of the class described comprising, a bar, a plurality of one part of a two-piece snap fastener arranged on said bar in a row longitudinally thereof, a plurality of tabs each of which has secured thereto a second part which is adapted to cooperatively engage said one part to provide a snap fastener, a pair of means on each of said tabs either of which is adapted to secure said tabs to a garment, and means on said bar whereby it may be attached to a suitable

support, said attaching means comprising a plurality of downwardly extending hooks proportioned to engage the cross-bar of a conventional coat hanger.

3. A garment hanger of the class described comprising, a bar, a plurality of one part of a two-piece snap fastener arranged on said bar in a row longitudinally thereof, a plurality of tabs each of which has secured thereto a second part which is adapted to cooperatively engage said one part to provide a snap fastener, each of said tabs having a buttonhole formed therein whereby said tab may be secured to a garment by means of a button, a safety pin attached to each of said tabs as an alternative means for securing said tab to a garment, and means on said bar whereby it may be attached to a suitable support, said attaching means comprising a plurality of downwardly extending hooks proportioned to engage the cross-bar of a conventional coat hanger.

4. A garment hanger of the class described comprising, a bar, a plurality of one part of a two-piece snap fastener arranged on said bar in a row longitudinally thereof, a plurality of tabs each of which has secured thereto a pair of second parts which are adapted to cooperatively engage said one part to provide a snap fastener, said second parts being oppositely disposed on the respective tab, a pair of means on each of said tabs either of which is adapted to secure said tabs to a garment, and means on said bar whereby it may be attached to a suitable support.

5. A garment hanger of the class described comprising, a bar, a plurality of one part of a two-piece snap fastener arranged on said bar in a row longitudinally thereof, said bar having two or more apertures formed therein intermediate the ends thereof to receive anchoring means whereby said bar may be secured to a hook rail, downwardly depending hooks formed on the upper edge of said bar whereby it is adapted to be suspended over the cross-bar of a coat hanger, and a strap having attached to each end thereof a second part adapted to cooperatively engage said one part to provide a snap fastener, whereby said strap is attached to certain of said one parts on said bar so as to suspend said bar from a rod.
